UNITED STATES PATENT OFFICE.

CHARLES POHL, OF LOS ANGELES, CALIFORNIA, ASSIGNOR TO JOHN O. KING, OF LOS ANGELES, CALIFORNIA.

DESIGN FOR AN AUTOMOBILE-LOCK.

56,888.

Specification for Design.

Patented Jan. 4, 1921.

Application filed March 25, 1920. Serial No. 368,754. Term of patent 3½ years.

To all whom it may concern:

Be it known that I, CHARLES POHL, citizen of the United States, residing at Los Angeles, county of Los Angeles, and State of California, have invented a new, original, and ornamental Design for an Automobile-Lock, of which the following is the specification, reference being had to the accompanying drawing, forming a part thereof.

Figure 1 is a plan view;
Fig. 2 is a side elevation;
Fig. 3 is an end view, showing my new design.

I claim;
The ornamental design for an automobile lock, as shown.

CHARLES POHL.
